[57] CLAIM

The ornamental design for a medical supply tray, as shown and described.

DESCRIPTION

FIG. 1 is a perspective view of my medical supply tray in accordance with my invention;

FIG. 2 is a front elevational view thereof;

FIG. 3 is a right side elevational view thereof, the left side elevational view being a mirror image thereto;

FIG. 4 is a rear elevational view thereof; and,

FIG. 5 is a top plan view thereof, the bottom plan view being flat and unornamented.
